POWER CONTROL WIRING DEVICE ADAPTED FOR MOUNTING IN A CONDUIT BOX

Donald Charles Long, Yardley, Pa., and Albert Charles Hartsough, Willingboro, and Robert Fincher Sanford, Titusville, N.J., assignors to Princeton Electro Dynamics, Inc.

Filed Oct. 3, 1973, Ser. No. 402,965

Term of patent 14 years

Int. Cl. D13—03

U.S. Cl. D26—13 R

Fig. 1.

Fig. 2.

Fig.3.

FIG. 1 is a perspective view of a power control wiring device adapted for mounting in a conduit box showing our new design.

FIG. 2 is a side elevational view thereof.

FIG. 3 is a bottom view of the power control wiring device according to our new design.

We claim:

The ornamental design for a power control wiring device adapted for mounting in a conduit box, substantially as shown and described.
